UNITED STATES PATENT OFFICE.

LOUIS KESSLER, OF CHICAGO, ILLINOIS, ASSIGNOR TO NON-EXPLOSIVE CAN AND TUBE COMPANY, OF CHICAGO, ILLINOIS, A CORPORATION OF ILLINOIS.

DEVICE FOR PREVENTING BACK-FIRING INTO GASOLENE-RECEPTACLES OR THE LIKE.

1,310,241.

Specification of Letters Patent. Patented July 15, 1919.

Application filed June 23, 1916. Serial No. 105,392.

To all whom it may concern:

Be it known that I, LOUIS KESSLER, a citizen of the United States, residing at Chicago, in the county of Cook and State of Illinois, have invented certain new and useful Improvements in Devices for Preventing Back-Firing into Gasolene-Receptacles or the like, of which the following is a description.

10 My invention belongs to that general class of devices for preventing explosions, and is a device especially intended for use at the outlet of receptacles containing gasolene or other explosive fluids or gases. 15 While the device is particularly adapted for use on any receptacle containing an explosive, such as gasolene or the like, to prevent the flame from entering the tank or receptacle from the discharge pipe, it is 20 desirable where the tank is connected with the carbureter of an explosive engine, to prevent back firing from the carbureter or engine into the tank, or otherwise prevent the entrance of flame. The invention has 25 among its objects the production of a device of the kind described for preventing back firing into a tank, that is simple, efficient, compact and satisfactory for the purpose, and which may be inexpensively 30 manufactured and installed in practically any system at comparatively small expense, and without much difficulty. Other objects and advantages of the device herein described will be obvious to those skilled in the 35 art to which the same pertains.

To this end my invention consists in the novel construction, arrangement and combination of parts herein shown and described, and more particularly pointed out 40 in the claims.

In the drawings, wherein like reference characters indicate like or corresponding parts,

Figure 1 is a sectional view through my 45 improved device, a portion of a receptacle and the discharge pipe therefrom;

Fig. 2 is a sectional view taken substantially on line 2—2 of Fig. 1;

Fig. 3 is a sectional view taken substantially on line 3—3 of Fig. 1, and

Fig. 4 is a perspective view of a perforated plate 13 and reinforcement and support therefor.

Referring to the drawings, 1 represents 55 the tank or receptacle, and 2 a part secured

thereto in any suitable manner, the same being tubular or provided with a chamber 3 therethrough. Carried by part 2 is a coöperating part 5, chambered as at 6, and formed with an outlet 7, the part being suitably connected with the feed pipe 8, extending from the tank to where desired, as for example, to the carbureter of an internal combustion engine. The parts 2 and 5 are preferably, although not necessarily, 60 made separable, as shown, and together constitute a tubular part having an inlet and outlet. Preferably arranged at the inlet 4, and extending transversely across the part, is a wire screen or gauze 9 of small mesh, 65 so that flame will not pass therethrough. The screen 9 may be arranged or secured in place in any desired manner.

Also extending across the tubular part in the path of fluid passing from the tank 75 to the discharge pipe 8, is a perforated protecting member or plate 13, or the equivalent, which is of some strength so as not to readily fracture, and which is carried by the part 10, formed with openings or notched 80 as at 11, or in an equivalent manner, as most clearly shown in Figs. 3 and 4. Part 10 is also provided with legs or lugs 12, which abut against the shoulder 16 on part 2. The perforated plate 13 may be secured 85 to part 10 in any desired manner, as for example by forming a lug 14 on part 13, and then upsetting the end, 15 being a washer, which may be inserted if desired. I have shown the perforated plate 13 of a size 90 to extend between the parts 2 and 5, as most clearly shown in Fig. 1, so that the same is supported at the edges.

In the normal operation of the system the 95 gasolene or other fluid freely flows from the tank through the gauze or screen 9, through the openings 11, and perforated plate 13, into the discharge or feed pipe 8, to where desired. In case of any back firing or entrance of flame through the pipe 8 toward 100 the tank, the force or shock of the back firing will be taken up by the plate 13, the flame, however, being prevented from entering the tank by the gauze 9. While the gauze in itself would prevent the flame 105 reaching the interior of the tank, the force of the back firing might be apt to fracture or displace the same. The plate 13, however, receives the impact or shock, the same being reinforced by means of the part 10, which is 110

solidly maintained in place by the lugs 12, abutting against the shoulder 16. The plate also prevents any fracture of the gauze from the exterior of the device when the discharge pipe is detached for cleaning or other purposes. The device is particularly adapted for automobile use, underground tanks, or the like, and eliminates any chance of back fire, causing an explosion in the gasoline tank.

Having thus described my invention, it is obvious that various immaterial modifications may be made in the same without departing from the spirit of my invention; hence I do not wish to be understood as limiting myself to the exact form, construction, arrangement and combination of parts herein shown and described, and uses mentioned.

What I claim as new and desire to secure by Letters Patent is:—

1. A device of the kind described comprising a chambered tubular part having a screened inlet and an outlet, in combination with a transverse partition arranged in said chamber and spaced from the screened inlet, said partition having a central closed body part and provided with a plurality of relatively small screened openings arranged about its periphery.

2. A device of the kind described comprising a chambered tubular part having a screened inlet and an outlet, in combination with a transverse partition arranged in said chamber and spaced from the screened inlet provided with a plurality of smaller screened openings arranged around its periphery, and bracing means for the trans-

verse partition supporting the same in an outward direction.

3. A device of the kind described comprising a chambered tubular part having a screened inlet and an outlet in combination with a removable transverse partition arranged to be placed in the chamber, provided with bracing legs extending outward and positioned against the supporting wall of the chamber, said partition being formed with a plurality of openings arranged about its periphery, and a screen covering said openings.

4. In a device of the kind described, a partition member provided with outwardly extending brace legs, and formed with openings about its periphery in combination with a screen arranged on the side opposite to the legs covering said openings, said screen being connected to the partition.

5. A device of the kind described comprising a chambered tubular part having a screened inlet, and a spaced outlet, in combination with an auxiliary screen spaced from the screened inlet, and a reinforcing member disposed between the said screens and in contact with the last mentioned screen, said reinforcing member being rigidly supported and having a central body part and spaced peripheral openings overlying said auxiliary screen.

In testimony whereof, I have hereunto signed my name in the presence of two subscribing witnesses.

LOUIS KESSLER.
